U.S. Cl. D26—13

FIG. 1

Des. 222,473

PAGE 2

FIG. 2

FIG. 3

FIG. 1 is a perspective view of an electric control panel board according to the present invention, with the cover in half-open position;

FIG. 2 is a perspective view of the electric control panel board shown in FIG. 1, with the panel in a nearly closed position; and

FIG. 3 is a perspective view of the electric control panel board shown in FIGS. 1 and 2, with the cover in open position.

I claim:

The ornamental design for an electric control panel board, as shown.
